UNITED STATES PATENT OFFICE.

DANIEL J. O'ROURKE, OF CHICAGO, ILLINOIS, ASSIGNOR TO SULLIVAN MACHINERY COMPANY, A CORPORATION OF MASSACHUSETTS.

FORGING MACHINE.

Application filed July 9, 1917. Serial No. 179,535.

My invention relates to forging machines.

It has for its object to provide an improved and simplified means whereby the axial opening in hollow drill steels may be expanded either during the process of manufacture or during that of re-sharpening. A further object of my invention is to provide an improved and simplified mechanism readily adapted to be installed upon or adjacent a sharpening machine and adapted to be controlled in a convenient manner by the work itself, all necessity for providing expensive separate apparatus, changing dollies, or providing any separate controlling mechanism requiring manipulation by the operator, being eliminated. A further object of my invention is to provide an improved mechanism for opening the holes in obstructed drill steels which will do away with some of the complications of present devices and which by operating the hole opening implement by means of a series of rapid blows will enable the operator to hold the steel in his hands unsupported during the hole opening operation and will permit the extraction of the device which opens the hole without resort to mechanical instrumentalities. These and other objects and advantages of my improved construction will, however, herein-after more fully appear.

In the accompanying drawings, I have shown, for purposes of illustration, one embodiment which my invention may assume in practice.

35 In these drawings,—

Fig. 1 is a side elevation of a drill sharpener of standard form equipped with my improved hole opening mechanism.

Fig. 2 is a side elevation of my improved hole expanding mechanism, the same being shown carried on its support and with a steel inserted over its expanding bit.

Fig. 3 is a plan view of the construction shown in Fig. 2, the view being taken at right angles to that shown in Fig. 2, with the support in section.

Fig. 4 is a detail view of the hole expanding bit.

Fig. 5 is a longitudinal sectional view of the expanding tool, the same being shown with the controlling mechanism in operating position.

In this illustrative construction, it will be noted that I have shown a drill sharpener of standard form, such as that constituting the invention of one Wade H. Wineman and now widely sold commercially, and including a base 1 having power operated clamping, upsetting, and swaging mechanisms thereon. Of these mechanisms, the clamping mechanism comprises a stationary clamping die 2 carried on the frame, and a cooperating movable clamping die 3 operated by suitable power means, while the upsetting mechanism comprises a reciprocating dolly 4 operated by power and adapted to upset the steel clamped between the dies 2 and 3. The swaging mechanism, as shown, also includes a stationary swaging die 5 and a movable swaging die 6 suitably operated by power. As in the construction mentioned above, the clamping and upsetting mechanism is shown to be controlled through a suitable controlling connection with a handle 7, while the swaging mechanism is controlled through a suitable controlling foot lever 8, suitable interlocking mechanism of a well known type preferably being provided between these two controlling mechanisms.

In my improved construction, I have provided improved means adapted to be associated with the drill sharpener whereby whenever desired, as, for instance, while the operator is upsetting the steel with the dolly, or during the swaging operation, he is enabled to expand the axial opening in hollow drill steels with great facility and without the necessity for changing the dolly 4 or operating any additional controlling levers, the expanding mechanism being set in operation by the work when the end of the drill steel is inserted over the expanding bit, and automatically cut out of operation when the steel is removed therefrom. As shown, a suitable support 9 is provided, preferably disposed adjacent the drill sharpener. This support carries thereon in a suitable bracket 10 a pneumatic tool, herein in the form of a hammer 11, suitable bolts 12 being herein shown inserted through the opening 13 in the supporting member 14 of the hammer to hold the latter in substantially fixed position in the desired plane. As shown, a suitable conical or otherwise shaped punch or hole ex-

panding bit 15, corresponding in contour to the desired shape of that portion of the bore extending through the ends of steels frequently subjected to reforging, is carried by 5 the tool 11 and disposed toward the operator so that he may conveniently press the hollow drill steel thereon or remove the same therefrom without a decided swinging movement of the steel.

10 In the form of my invention shown herein, the hammer 11 comprises a suitable cylinder 16 reciprocable relative to the member 14 and having suitable fluid passages (shown only in part) arranged to cause a 15 hammer piston 17 to reciprocate into and out of engagement with the inner end 18 of the expanding tool 15. This tool as shown is in turn carried in a suitable non-rotating chuck 19 and is provided with a flange 20 on its inner end adapted alternately to engage the 20 front end of the chuck and a suitable flange 21 on a removable cap or housing 22. As shown, air or other pressure fluid is supplied to this hammer through a suitable inlet plug 25 carried on the cylinder, a limited longitudinal movement between the cylinder and the handle being permitted by a slot 24 through which the plug 23 extends. It will also be noted that a throttle valve 25 is disposed at the rear end of the cylinder; and 30 upon rearward axial movement of the hammer relative to the supporting member 14, the supply of motive fluid past the valve is opened, and upon movement of the hammer in the opposite direction, the supply of fluid to the hammer is cut off. Air pressure is supplied to the forward area of the valve from the plug 23 through a port 26. If desired, a suitable controlling mechanism, such 40 for example as is disclosed in the patent to Gilman 902,288, Oct. 27, 1908, and for purposes of illustration shown herein as a valve 27, receives air from the valve 25 through a passage 28 and is adapted alternately to admit pressure fluid to the opposite ends of the cylinder 16 in a well known manner and thereby cause reciprocation of the hammer piston 17 in the cylinder. It will thus be observed that in this construction the cylinder 16 and member 14 are relatively reciprocable, and that when pressure is applied to the bit 15 or removed therefrom through the movement of the cylinder, the throttle valve 25 is so positioned relative to said cylinder as to cause air to be admitted from the supply plug 23 to the valve 27 to start the hammer piston in motion or to cause the air supply to be cut off to stop the movement of the piston.

50 In the operation of my improved construction, it is possible for the operator to apply a hollow drill steel, herein indicated at A, to the end of the expanding tool 15 while the latter is at rest and, by pressing

the steel against this end when the latter is 65 in registry with the axial opening B in the steel, cause the cylinder 16 to be moved relative to the member 14 and thereby set the hammer mechanism in operation in such a manner as to cause the hole expanding bit 15 by repeated blows to work its way into the axial opening in the steel and expand the same as desired. It will also be noted that when the operator desires to remove the steel from the expanding bit 15, it is only 70 necessary for him to pull on the steel in order to remove the steel and thereby move the cylinder 16 in the opposite direction and cut the piston 17 out of operation. It will be obvious that with this improved mechanism the operator by reason of the rapid series of 75 relatively light blows can without discomfort or difficulty hold the steel in his hands and so dispense with clamping mechanisms which have previously been employed. It 80 will also be obvious that the repeated light blows will open the hole in such manner as to prevent sticking of the bit expanding tool 15 therein.

In addition to the foregoing modes of operation, it is to be noted that the structure also makes possible operation in the following manner: Should the punch pin lodge in the opening, as may occur, the operator can remove the punch pin from the bore with 90 greater ease by making use of the hammer to impart a jarring effect tending to loosen the pin. Assuming that the punch has been driven into the steel, the operator by pulling outwardly on the steel would cause the pin 100 to be pulled out of range of the hammer. In order then to continue the operation of the hammer the operator, while pulling outwardly on the steel, may place his foot against the housing 22 and move the cylinder 16 rearwardly thereby causing communication between the passageways leading from the opening 23 and transversely of the bore of the valve 25 to the hammer. Fluid flowing through said passages will cause reciprocation of the hammer, but due to the fact that the pin is out of range of the hammer no direct impact action will be imparted thereto. However, the cushioning action on the rearward stroke of the hammer piston is 110 sufficient to impart a jarring action to the pin through the housing 22 which has contact with the pin collar 20. It will also be noted that the operator in pressing rearwardly on the housing 22 with his foot and 115 pulling outwardly on the drill steel can control to a practical nicety the position of the cylinder 16 in the supporting member 14 to such an extent that the cylinder need not be moved to its rearmost position, but may be spaced a slight distance from the end of the bore before mentioned, thereby permitting the hammer mechanism to be yieldably mov-

able in a rearward direction during removal of the pin and operation of the motor.

By my improvement, it will be noted that all necessity for providing separate punches 5 operated by air or oil and controlled through the manipulation of separate controlling mechanism, changing dollies, or the provision of separate punching mechanism operatively connected to the drill sharpener and 10 requiring manipulation by the operator of separate controlling mechanism, is effectually overcome, the expense necessary to provide a punching attachment being thereby very materially decreased at the same time 15 that the work of the operator is greatly facilitated. It will also be evident that, if desired, my improved punching mechanism may be used in connection with a sharpener of any type, and that the same may be conveniently located in any desired position and either on the frame of the sharpener or adjacent thereto. These and other advantages 20 of my improved construction will, however, be clearly apparent to those skilled in the 25 art.

While I have in this application specifically described one embodiment which my invention may assume in practice, it is to be understood that the same is shown herein 30 for purposes of illustration and that the invention may be modified and assume various other forms without departing from its spirit, it being my intention to include all such modifications within the scope of the 35 appended claims.

What I claim as new and desire to secure by Letters Patent is:

1. A bore opening mechanism for hollow drill steels comprising the combination of 40 a support, an elongated bore opening pin mounted thereon, holding means permitting relative movement axially between said pin and support, a hammering device on said support comprising means for imparting a 45 series of impacts directly on said pin, said holding means permitting said pin to remain lodged in the drill steel bore while permitting relative movement between said pin and support.

50 2. A bore opening mechanism for hollow drill steels comprising the combination of a support, an elongated bore opening pin mounted thereon, holding means permitting relative movement axially between said 55 pin and support, a hammering device on said support comprising means controlled through engagement of the pin in a bore for imparting a series of impacts directly on said pin, said holding means permitting relative movement between said pin and support and constituting means permitting movement of said pin and steel in unison 60 relatively to said support to shift said pin from the range of impact action of 'said hammering mechanism.

3. A bore opening mechanism for hollow drill steels comprising the combination of a support, an elongated bore opening pin mounted thereon, a hammering mechanism also mounted thereon and adapted to impart 70 a series of impacts directly on one end of said pin for driving the same into an obstructed drill steel bore and into binding contact with the periphery thereof, and pin holding means permitting positive relative 75 movement between said pin and hammer prior to withdrawal of said pin from the bore, the steel and pin moving together during the existence of said binding contact.

4. A bore opening mechanism for hollow 80 drill steels comprising the combination of a support, a horizontally extended elongated punch pin mounted thereon, a hammering mechanism also mounted thereon and adapted to impart a series of impacts directly on one end of said pin for driving the same into an obstructed drill steel bore and into binding contact with the periphery thereof, pin holding means permitting positive relative 85 movement between said pin and hammer into and out of operative relation to be effected by movement of the steel prior to withdrawal of said pin from the bore, said positive relative movement necessitating the 90 existence of said binding action.

5. A bore opening mechanism for hollow 95 drill steels comprising a support, hammering mechanism thereon having two cooperating portions relatively movable axially, one enclosing blow imparting means, an 100 elongated punch having one end mounted in one of said cooperating portions for limited movement axially towards and from the blow imparting means, and means for controlling actuation of the blow imparting 105 means through relative movement between the cooperating portions of said hammering mechanism.

6. A bore opening mechanism for a hollow 110 drill steel comprising a support, an elongated punch pin mounted thereon, a pneumatic hammer mounted in cooperating relation thereto, means whereby the same is actuated to impart a series of impacts to one end of said pin, and means permitting 115 actuation of said hammer during withdrawal of said pin from said bore.

7. A bore opening mechanism for a hollow 120 drill steel comprising a support, an elongated punch pin mounted thereon in horizontal position, a pneumatic hammer mounted in cooperating relation thereto, means whereby the same is actuated to impart a series of impacts to said pin, means permitting 125 actuation of said hammer during withdrawal of said pin from said hole, and means permitting said pin to be placed out of range of the hammer during withdrawal.

8. A bore opening mechanism for hollow 130 drill steels comprising a support, an elong-

gated punch pin mounted thereon in horizontal position, a pneumatic hammer mounted in cooperating relation thereto, means for longitudinally slidably supporting said hammer, means for setting said hammer in operation upon longitudinal movement thereof, to impart a series of impacts directly on

said pin to drive the same into an obstructed drill steel bore, and means permitting withdrawal of the pin from range of the hammer while maintaining operation of the hammer. ¹⁰

In testimony whereof I affix my signature.
DANIEL J. O'OURKE.
